UNITED STATES PATENT OFFICE.

WILLIAM N. HUNTER, OF BLANCHESTER, OHIO.

HAND BAG.

Application filed December 12, 1923. Serial No. 680,242.

To all whom it may concern:

Be it known that I, WILLIAM N. HUNTER, a citizen of the United States, and a resident of Blanchester, in the county of Clinton 5 and State of Ohio, have invented certain new and useful Improvements in Hand Bags, of which the following is a full, clear, and exact description, reference being had to the accompanying drawings, forming part 10 of this specification.

My invention relates to the construction of hand bags such as Gladstone bags, in which when the contents are removed the bag can be folded up into a portfolio for the 15 reception of documents, papers, drawings and the like. The construction is such that for traveling from place to place the papers, drawings and the like can be carried flat in the bottom of the bag with the other contents on top, and when the destination is 20 reached, the contents of the bag can be removed and the bag converted into a convenient portfolio for the papers, and thus it will not be necessary for the traveler to 25 carry both a bag and a portfolio.

The invention consists of that certain novel construction and arrangement of parts to be hereinafter particularly pointed out and claimed, in which the sides and ends 30 of the bag are reinforced with foldable stiff flaps on the inside. These flaps can be erected to form with the stiff rectangular bottom the lower portion of the Gladstone bag. The ends and sides for the upper 35 section are flexible and with the stiff ends and sides folded along the bottom, the bottom can then be folded and secured along one of the sides, so that the bag can be contracted into a portfolio.

40 In the drawings:

Figure 1 is a perspective view of the hand bag closed, taken from one side.

Figure 2 is a similar view taken from the other side.

45 Figure 3 is a perspective cross sectional view taken on the line 3—3 of Figure 1.

Figures 4 and 5 are central longitudinal sections looking in opposite directions as indicated by the arrows 4 and 5 in Figure 3.

50 Figure 6 is a perspective view of the bag in process of folding into a portfolio.

Figure 7 is a perspective view of the

portfolio taken from one side with the closing flap open.

55 Figure 8 is a similar view with the portfolio closed.

Figure 9 is a cross section of the portfolio as shown in Figure 7.

Figure 10 is a perspective view of the rods 60 for hinging together the end folds.

Figure 11 is a detail of the hinge parts of same.

The bag is constructed of leather, cloth, 65 canvas, or other suitable material, and of and desired size, but preferably with a rectangular bottom of a size to hold flat any documents, drawings or the like, that it may be desired to carry. This rectangular bottom 1 is made of stiff board of any suitable material covered with leather or other 70 finishing material, and suitably lined and preferably provided with knobs 2, 2 upon which to rest the bag. The sides 3, 3, and ends 4, 4, of the bag are made of leather or other material to conform to the bottom 75 and extend upward to the usual height of such bags, with the ends 4, 4, provided with a central vertical fold line 5 and diagonal fold lines 6, 6, for the lower half and diagonal fold lines 7, 7 for the upper half. There is also a horizontal fold line 8 between the upper and lower half of the bag. As thus far described, the bag is a rectangular container open at the top with a 80 stiff bottom, flat sides and ends which will fold with bellows folds to allow the sides to be brought together at the top. It will be understood that the inside is properly lined with leather, canvas or other material. 85

90 On the inside of the bag is hinged along one side of the bottom, a stiff rectangular flap 9, which extends the full length of the bag and is of the height of the lower half thereof, and a pair of similar stiff flaps 95 10 and 12 of the same height, and extending across the ends are hinged to the ends of the bottom. The opposite side of the lower section is also reinforced with stiff cardboard 13, or other suitable material.

100 To form the stiff lower half of the Gladstone bag, the side 9 is raised and locked along the side by the fasteners 14, and the end flaps 10 and 12 are also erected and caught behind the side flap 9, and a rectangular portion is obtained for the lower 105

half of the bag with stiff side and end walls. The upper side edges can then be brought together and the upper portion of the ends will fold inward in triangular folds on the 5 fold lines 5, 7, 7, and 8.

To close and lock the bag one of the sides is extended to form an over fold flap 15, and this flap is provided with any usual form of catch 16, to engage a corresponding lock 17 10 near the upper edge of the other side. There are a pair of these locks, one near each end. A handle 18 is also provided for the bag. For properly stiffening the flexible material of the sides of the bag, I prefer to use stiffening strips 19, sewed between the lining and the leather, and the inside of the bag in addition to being lined throughout will be provided with such number of open side pockets 21 as may be convenient. The upper edges 15 of the ends of the bag are also reinforced with metal rods 20, hinged together at the middle fold. The ends of these rods have right angled downward extensions 30, which are seated in pockets at the corners and the 20 inner ends of the rods are flattened out to form hinge members 31 formed with shoulders to serve as stops to permit the rods to fold inwardly only. A rivet 32 with spring washers 33, is employed to hinge the members 30 together and the flattened surfaces of the hinge members when the bag is open are in a diagonal plane from the horizontal, so that when the bag is opened it will be 25 locked open, until the hinged members are pushed downwardly as well as inwardly.

When desired a pair of straps 23, 23, can also be employed held at various points around the bag by fasteners 24 and provided with buckles 25.

40 In order to convert the bag into a portfolio, the contents are removed, the stiff end flaps 10, 12 and the side flap 9 are folded along the bottom, and the sides and ends folded down into the position shown in Figure 6. The bottom 1 is then folded up along the middle line of fold 26 and secured along the side by flaps 27, 27, provided with fasteners to engage corresponding fastening members on the bottom, and a portfolio will 45 be provided closed and locked by the over fold 15 of the bag. I have also shown a flap 28 which may cover a name plate or card of the owner and which is normally held shut by a fastener 29.

55 In illustrating and describing the details, I do not wish to be understood as limiting my invention to these details, as it is evident that very many modifications can be made in the details without departing from the 60 spirit of my invention.

Having thus described my invention, what I claim as new and desire to secure by Letters Patent, is:—

1. In a hand bag of the kind specified, a 65 body portion of flexible material for the

sides and ends, with a stiff and inflexible bottom portion, and foldable means for stiffening the ends of the lower section of the bag, whereby upon folding of the stiffening means, the bottom can be folded along one side to form a portfolio. 70

2. In a hand bag of the kind specified, a body portion of flexible material for the sides and ends, with a stiff and inflexible bottom portion, and stiff flaps for the ends 75 to form a stiff lower section for the bag, the stiff end flaps adapted to be folded along the bottom to permit the bottom to be folded along one side to form a portfolio.

3. In a hand bag of the kind specified, a body portion of flexible material for the sides and ends, with a stiff and inflexible bottom portion, and stiff flaps for the ends to form a stiff lower section for the bag, the upper portion of the ends folded in 80 bellows folds, and the sides brought together at the top to close the bag, and the stiff end flaps adapted to be folded along the bottom to permit the bottom to be folded along one side to form a portfolio. 85

4. In a hand bag of the kind specified, a body portion of flexible material for the sides and ends, a stiff and inflexible bottom portion and stiff flaps for the ends to form a stiff lower section for the bag, the stiff end flaps adapted to be folded along the bottom to permit the bottom to be folded along one side to form a portfolio, with 90 means for retaining the bottom in folded position. 95

5. In a hand bag of the kind specified, a body portion of flexible material for the sides and ends with a stiff and inflexible bottom portion, stiff flaps for one side and each end hinged to be erected to form a stiff lower section for the bag, the stiff side and end flaps adapted to be folded along the bottom to permit the bottom to be folded along one side to form a portfolio. 100

6. In a hand bag of the kind specified, a body portion of flexible material for the sides and ends, a stiff and inflexible bottom portion, and stiff flaps for the ends to form a stiff lower section for the bag, the upper portion of the ends folded in 105 bellows folds, and the sides brought together at the top to close the bag, and the stiff end flaps adapted to be folded along the bottom to permit the bottom to be folded along one side to form a portfolio, one side 110 being extended at the top to fold over the opposite side to more effectively close the bag. 115

7. In a hand bag of the kind specified, a body portion of flexible material for the sides and ends with a stiff and inflexible bottom portion, stiff flaps for one side and each end hinged to be erected to form a stiff lower section for the bag, the stiff side and end flaps adapted to be folded along 120 125 130

bottom to permit the bottom to be folded stiff lower section for the bag, the stiff side along one side to form a portfolio, with end flaps adapted to be folded along means for securing the stiff bottom to the bottom to permit the bottom to be folded side accessible without interference from the along one side to form a portfolio, the top folding flap cut away at the ends, and tabs 15

5 top folding flap.

8. In a hand bag of the kind specified, a body portion of flexible material for the sides and ends with a stiff and inflexible bottom portion, stiff flaps for one side and 10 each end hinged to be erected to form a

WILLIAM N. HUNTER.
